Patented Mar. 15, 1921.

2 SHEETS—SHEET 2.

UNITED STATES PATENT OFFICE.

ALBERT HUPP, OF WASHINGTON, DISTRICT OF COLUMBIA, ASSIGNOR, BY MESNE ASSIGNMENTS, TO AUTOMATIC RAILWAY MAIL EXCHANGE COMPANY, OF CHICAGO, ILLINOIS, A CORPORATION OF ILLINOIS.

STATION-TROUGH.

1,371,486.

Specification of Letters Patent. Patented Mar. 15, 1921.

Application filed July 10, 1915, Serial No. 39,111. Renewed August 7, 1920. Serial No. 402,033.

To all whom it may concern:

Be it known that I, ALBERT HUPP, a citizen of the United States, and resident of Washington, District of Columbia, have invented certain new and useful Improvements in Station-Troughs, of which the following is a specification.

This invention relates to railway mail exchange apparatus and more particularly to the receiving trough which is located along the railroad track and receives the mail from the moving train. It is the object of the invention to provide a trough of substantial construction which will be capable of arresting the motion of the packages or sacks of mail without injury of the contents.

A further object of the invention is to provide a construction which supports the cranes for holding the mail sacks in position to be taken by the train apparatus, the trough with the cranes thereon being vertically adjustable to accommodate variations in the level of the track.

Other objects and the features of novelty will be apparent from the following description taken in connection with the accompanying drawings, in which:

Figure 1 is a side elevation of a trough embodying my invention.

Fig. 2 is an enlarged cross-sectional view on the line 2—2 of Fig. 1, the railway car and the mail handling apparatus thereon being also shown in its relation to the trough.

Fig. 3 is a view similar to Fig. 2 but taken on the line 3—3 of Fig. 1.

Fig. 4 is an enlarged side elevation of an end of the trough.

Fig. 5 is an end elevation of a trough embodying a modified form of the invention.

Fig. 6 is a plan view of the construction shown in Fig. 5.

Referring to Figs. 1 to 4, 10 indicates a track, 11 the body of a car on the track, 12 the mail receiving arm or chute and 13 the delivering chute on the car. Arranged

at a distance of several feet from the track are two rows of supporting members 14 and 15, these members being spaced apart longitudinally of the track and the members 14 carrying posts 16 which support the front of the trough for receiving the mail bags from the delivering chute 13. The supporting members 15 support the posts 17, and beams 18, downwardly inclined away from the car, are connected to each pair of the posts 16 and 17. The beams 18 extend to the rear of the posts 17 and are connected with the upper ends of the latter by braces 19.

Secured to the beams 18 and extending longitudinally of the trough are the bottom boards 20, these boards being slightly spaced apart along their longitudinal edges to permit rain to drain from the trough. A series of longitudinally extending boards 21 are secured to the posts 17 and form the vertical back of the trough. From Fig. 2 it will be apparent that the bottom of the trough forms, with the back, an acute angle and when the mail bags are discharged from the chute 13 onto the bottom of the trough they will slide down into this acute angle and then move longitudinally of the trough, the friction between the bags and the boards 20 and 21 retarding the motion of the bags.

Arranged along the upper edge of the bottom of the trough is a suitable rail 22 which serves to prevent the bags from falling from the front side of the trough. The posts 17 have secured to the upper ends thereof the cross pieces 23 which carry the boards 24, the latter forming a platform on which the mail cranes 25 are supported. The cranes 25 are for the purpose of holding the sacks which are to be taken by the receiving chute 12 of the car.

In order to avoid undue shocks to the contents of the mail bags when they are discharged from the chute 13 onto the bottom of the trough, it is desirable to maintain the trough at a certain elevation with reference to the bottom of the chute 13 and since the actual elevation of the bottom of

the chute varies with the elevation of the rails, it is evident that, in order to provide for changes in the elevation of the rails, means must be provided for raising or lowering the trough as a whole. The relation of the chutes 12 and 13 on the car is fixed, as to elevations, and, therefore, in adjusting the trough to the elevation of the bottom of the chute 13, the cranes 25 will be 10 simultaneously adjusted with reference to the chute 12 so that the adjustment of the trough will maintain the cranes in proper elevation.

Connection between the posts 14 and 16 15 is made by members 26 extending along the front of the trough and secured to the posts by bolts or lag screws or any other suitable devices. The posts 15 and 17 are connected in any adjusted position by means 20 of tie blocks 27 which may also be secured in the same manner as the members 26. If the arms of the crane are not at the correct elevation to coöperate with the chute on the car, the entire trough with the crane 25 may be raised by withdrawing the lower bolts, lag screws or other fastening means that is used from the members 26 and tie blocks 27. Thus the members 26 will be fastened to the posts 16 but free from the 30 supports 14. Similarly the tie blocks 27 will remain attached to the posts 17 but free from the supports 15. The trough may then be raised and the members 26 and tie plates fastened to the supports to hold the trough and crane in the desired adjusted 35 position.

In order to avoid having the troughs of excessive length, in providing for the necessary space in which to stop the motion of the 40 mail bags, it is desirable to have the bottom of the trough turned up at the end as indicated at 28.

Referring to Fig. 4 it will be seen that the 45 curved portion 28 of the bottom is arranged on an arc of a true circle and that the force of gravity will be brought into action to assist the frictional resistance of the bags on the bottom of the trough, to stop the bags. In practice the bags slide up the curved 50 end portion and then slide back to a position of rest from which they may be removed.

On account of the bottom of the trough being turned up at the end it is also necessary 55 to incline the front and back walls of the trough to prevent the bags from falling to the ground.

In Fig. 4 it will be seen that the boards 29 60 are inclined upwardly from the point 30 and are secured to the posts 31. The boards 32 constituting the back wall of the trough are also inclined upwardly and secured to posts 31 and the cross boards forming the curved portion 28 of the bottom are secured 65 to the boards 29 and 32 in any suitable man-

ner and supported thereby. The inclining of the front wall of the chute upward necessitates that this wall also be deflected away from the train, otherwise it would be struck by the chute 13. This deflection of 70 the front wall 29 away from the train is clearly indicated in Fig. 3.

In Figs. 5 and 6 there is illustrated another form of end for the trough in which the mail bags have their direction of motion reversed on a substantially horizontal continuation of the bottom. Referring to these figures it will be seen that the posts 33 carry cross beams 34 which support the boards 35 arranged substantially horizontal 80 and on the plane of the apex of the angle between the bottom and side walls of the trough as clearly shown in Fig. 5. The front wall 36 is deflected away from the track, as clearly shown in Fig. 6 and inclined upwardly from the point 37, as indicated in Fig. 5 and by this arrangement the proper clearance is provided for the chute 13. At the extreme end of the trough a semi-cylindrical plate 38 constitutes a continuation 90 of the wall 36 and provides a smooth surface for reversing the motion of the mail bags and delivering them to the open space 39 substantially in the rear of the point 37. The boards 40 extend from the plate 38 to 95 the opening 39 as shown in Fig. 6. In order to reinforce the plate 38 angle irons 41 and 42 are secured along the top and bottom edges respectively and the bottom boards 35 are secured to the under side of the angle 100 iron 42.

In this construction of the trough end the bags are brought to rest in front of the opening 39 and may be conveniently removed from the rear of the trough so that it is unnecessary for the attendant to approach the trough from the track side thereof in order 105 to get the mail bags. The posts 33 are formed in two sections as indicated at 43 and these sections are secured together by 110 suitable plates 44 which permit the trough to be adjusted throughout its length.

Having thus described my invention, what I claim and desire to secure by Letters Patent is:

1. A trough for receiving mail from rapidly moving trains, comprising a bottom inclined downwardly away from the train and having a curved end portion to carry the mail away from the track, a substantially vertical back, and the front being parallel with the track throughout the greater portion of its length and arranged at an angle to the track and gradually increasing in height at the end of the trough. 120

2. A trough for receiving mail, from rapidly moving trains, comprising a bottom inclined downwardly away from the train and having its end portion turned upwardly, a substantially vertical back and the front 125

130

being parallel with the track throughout the greater portion of its length and arranged at an angle to the track and gradually increasing in height at the end of the trough.

5 3. A trough for receiving mail, from rapidly moving trains, comprising a bottom having its end portion curved upward on the arc of a circle, a substantially vertical back,

and the front being parallel with the track throughout the greater portion of its length 10 and arranged at an angle to the track and gradually increasing in height at the end of the trough.

In testimony whereof I affix my signature.

ALBERT HUPP.
